CHARLES R. EVERSON, OF PALMYRA, NEW YORK.

Letters Patent No. 65,894, dated June 18, 1867.

IMPROVEMENT IN FASTENINGS FOR PAPER COLLARS.

The Schedule referred to in these Letters Patent and making part of the same.

TO ALL WHOM IT MAY CONCERN:

Be it known that I, CHARLES R. EVERSON, of Palmyra, in the county of Wayne, and State of New York, have invented a new and improved Fastener for Collars, etc.; and I do hereby declare that the following is a full, clear, and exact description thereof, which will enable others skilled in the art to make and use the same, reference being had to the accompanying drawings, forming part of this specification.

The present invention relates to a fastener for holding the two ends of a collar together, and securing such ends of the collar to the front button of the shirt-band, without passing their button-holes over such button, whereby the button-holes are relieved of all strain, and consequent breaking or tearing out from use, especially when the collar is made of paper. In the accompanying plate of drawings my improved fastener for collars, etc., is illustrated—

Figure 1 being a front view of the same in connection with a collar.

Figure 2, a view of the rear side of the fastener; and

Figure 3, a vertical section, taken on the plane of the line x x , fig. 1.

Similar letters of reference indicate like parts.

A, in the drawings, represents my improved fastener, which consists of a plate, B, of metal or other suitable material, having hinged to one of its edges C a clasp-plate, D, of suitable length to extend across the plate B, and fasten, by the other end E, over the opposite edge F of the said plate B. G, an India-rubber loop, secured to centre of plate B, from the rear side of which it projects or hangs.

In using the fastener above described, for collars, the two ends of the collar are first overlapped, so as to bring their button-holes in the same line with each other, when through such button-holes pass the clasp D, and, bringing it down over the front side, catch it over the lower edge of the plate B, when, as is obvious, the two ends of the collar are fastened together, and can be then secured by the loop to the fastener over the front button of the shirt, or previous to the insertion of the clasp in the button-holes, as hereinabove described.

By the use of my improved collar-fastener no strain is produced upon the button-holes to the collar, and consequently their tearing or breaking out or away from use and wear is, in a great measure, obviated.

It may be here observed that, although my fastener has been described with especial reference to collars, it may be used for other articles of wearing apparel, such as cuffs, etc.

I claim as new, and desire to secure by Letters Patent—

A fastener for collars, composed of plate B, having a clasp, D, hinged to it, and provided with a loop, G, substantially as described.

CHAS. R. EVERSON.
